TIMOTHY HENRY REARDON, OF NORTH ADAMS, MASSACHUSETTS.

APPARATUS FOR MEASURING OHMIC RESISTANCE OF LIQUIDS AND SOLUTIONS.

1,346,057.

Specification of Letters Patent.

Patented July 6, 1920.

Application filed November 8, 1918. Serial No. 261,672.

To all whom it may concern:

Be it known that I, TIMOTHY HENRY REARDON, a citizen of the United States, and a resident of North Adams, in the county 5 of Berkshire and State of Massachusetts, have invented a new and Improved Apparatus for Measuring Ohmic Resistance of Liquids and Solutions, of which the following is a full, clear, and exact description.

10 The object of the invention is to provide a new and improved apparatus for measuring ohmic resistance of liquids and solutions in a very simple, efficient and quick manner, thus enabling the user to determine whether 15 such liquid or solution is suitable for a particular purpose.

In the use of electrolytes in batteries of both primary and secondary types, the ohmic resistance is a detriment as it is productive of heat and wasteful of electrical 20 energy. Hydrometric readings fail to reveal the status of such liquids or solutions as regards their suitability in a battery. The absorption of carbon dioxide from the 25 atmosphere in alkaline electrolytes tends to maintain the density of the electrolyte, while the loss of solid substance which occurs as a result of spraying, gassing, etc., tends to lower the specific gravity. The resulting 30 density thereof is dependent upon one factor that tends to increase the density and upon another factor that tends to lower the density. For this reason the hydrometer reading by itself is no criterion by which the 35 character of the electrolyte can be judged.

In electrochemical work, such as the electrolysis of sodium chlorid (NaCl) for the production of sodium hydrate (NaOH), chlorin (Cl), sodium hypochlorite (NaOCl), 40 sodium chlorate (NaClO₃), etc., it is of the greatest importance that the ohmic resistance of the solution be kept at the lowest possible point consistent with economy in the use of salt. In the electrolytic production 45 of hydrogen and oxygen by the electrolysis of a solution of sodium hydrate (NaOH) the same reasoning holds good, that ohmic resistance produces heat and is wasteful of electrical energy. With the apparatus presently described in detail the 50 ohmic resistance of a liquid or solution can be quickly determined.

A practical embodiment of the invention is represented in the accompanying drawing 55 forming a part of this specification, in which the figure is a sectional side elevation

of the apparatus with parts shown diagrammatically.

The liquid or solution 10 of which the ohmic resistance is to be determined is contained in a vessel 11 of metal or other suitable conductive material. A tube 12 of glass or other non-conductive material is immersed with its lower end in the liquid 10 contained in the vessel 11, and the upper 60 end of the tube 12 is provided with a metal disk 13 having a small opening 14, and this disk 13 is held in place on the tube by a cap 15 made of metal, carbon or other suitable conductive material. The cap 15 is 70 fitted tightly on the upper end of the tube by a packing ring 16 and the top of the cap 15 is provided with a short tube 17 connected with one end of a flexible tube 18 adapted to be connected with a suction device of any approved construction for drawing the liquid contained in the vessel 11 up in the tube 12 and into the cap 15. When this has been done the tube 18 is closed by a suitable closing device 19 to hold the liquid 80 in column form in the tube 12. It is understood that the amount of liquid contained in the tube 12 is predetermined by using a correspondingly sized tube.

In order to determine the ohmic resistance 85 of this column of liquid or solution contained in the tube 12, the following arrangement is made: A source of electrical energy is connected by the circuit wires 25 and 26 with the pivots 27, 28 of a double blade, 90 double throw switch 29 of usual construction and adapted to be connected with contacts 30, 31 or 32, 33. The contacts 30, 31 are connected by wires 40, 41 with an indicating device 42 such as a voltmeter, Wheat- 95 stone bridge, ohmmeter or the like. Thus when the switch 29 is in the position shown in the drawing the electric current from the source of electrical energy passes through the indicating device 42 to permit the user 100 to read the voltage of the current.

The wire 41 is connected by a wire 45 with a brush 46 of a pole changing device 47 of usual construction and having a shaft 48 provided with a pulley 49 connected by belt 105 50 with other machinery for rotating the shaft 48. On the shaft 48 are secured the cylinders or rings 51 and 52 having overlapping inner ends and insulated one from the other by a suitable insulation 53 at the 110 overlapping ends. The outer end of the cylinder 51 is engaged by the brush 46 and the

outer end of the cylinder 52 is engaged by a brush 54 connected by a wire 55 with the switch contact 33. The inner overlapping ends of the cylinders 51, 52 are alternately engaged by brushes 60, 61, of which the brush 60 connects by a wire 62 with the vessel 11 and the brush 61 connects by a wire 63 with the cap 15. It will be noticed that when the switch 29 is disengaged from the contacts 30, 31 and swung into engagement with the contacts 32, 33 then an electric current passes from the main line to the vessel 11 through the liquid 10 to the cap 15 by way of the pole changer 47 and wires 45, 41 15 to the indicating device 42 to indicate the ohmic resistance of the liquid or solution contained in the tube 12. It is understood that by the use of the pole changer 47 the electric current passing through the liquid 20 or solution 10 in the tube 12 is rapidly reversed thus preventing development of polarization.

It will be noticed that by the arrangement described the operator is enabled to 25 first determine the voltage of the main current and then by the changing of the switch 29 and the sending of the current through the column of liquid or solution 10 a second reading is obtained at the indicating device 30 42 to indicate the voltage of the liquid. It is understood that with the switch in lower position, the column of liquid is placed in series with the indicating device 42 and a much lower voltage reading is obtained. It 35 is understood that from the two readings obtained at the indicating device the electrical resistance of the column of liquid or solution in the glass tube 12 can be readily calculated, it being known that in the case 40 of distilled water contained in a tube twelve inches in length and of one quarter inch bore the electrical resistance is about 1,830,180 ohms. By making the length of the tube 12 sufficiently great and reducing 45 the cross sectional area of the bore, the current passing through the liquid column can be made so infinitesimally low in value that the counter electromotive force of polarization is practically *nil*.

50 It will be noticed that the apparatus is for the rapid measurement of resistance in a way that will appeal to the judgment and capacity of the ordinary man. A degree of accuracy is obtained that readily satisfies industrial requirements. Temperature errors 55 can be eliminated by making a test on a standard stock solution and a test on a sample both at the same time.

Having thus described my invention, I 60 claim as new and desire to secure by Letters Patent:-

1. An apparatus for measuring ohmic resistance of liquids and solutions, comprising a vessel of conductive material and 65 adapted to contain the liquid or solution, a

tube of non-conducting material having one end inserted in the said liquid or solution and adapted to be filled with the same, conducting material in contact with said liquid or solution at the other end of the tube, an 70 electric circuit connected at one end with the said vessel and at its other end with the conducting material in contact with the liquid or solution, and means for measuring the voltage or potential difference of the 75 said current in passing through the liquid or solution.

2. An apparatus for measuring ohmic resistance of liquids and solutions, comprising a vessel of conductive material and 80 adapted to contain the liquid or solution, a tube of non-conducting material having one end inserted in the said liquid or solution and adapted to be filled with the same, conducting material in contact with said liquid or solution at the other end of the tube, an 85 electric circuit connected at one end with the said vessel and at its other end with the conducting material, in contact with the liquid or solution, said electric circuit connected with a source of electrical energy, a 90 switch connected with the said circuit, an electric resistance indicating device connected with the said switch to permit of reading the voltage of the current of the 95 said electric circuit when the switch is in one position, and a second circuit connected with the said indicating device and the said switch when the latter is in another position to permit of reading the voltage of the 100 second circuit passing through the said column of liquid or solution.

3. An apparatus for measuring ohmic resistance of liquids and solutions, comprising a vessel of conductive material and 105 adapted to contain the liquid or solution, a tube of non-conducting material having one end inserted in the said liquid or solution and adapted to be filled with the same, conducting material in contact with said liquid or solution at the other end of the tube, an electric circuit connected at one 110 end with the said vessel and at its other end with the conducting material, in contact with the liquid or solution, said electric circuit connected with a source of electrical energy, a switch connected with the said circuit, an electric resistance indicating device connected with the said switch to permit of reading the voltage of the current of the 115 said electric circuit when the switch is in one position, a second circuit connected with the said indicating device and the said switch when the latter is in another position to permit of reading the voltage of the 120 second circuit passing through the said column of liquid or solution.

4. An apparatus for measuring ohmic re- 125

sistance of liquids and solutions, comprising a vessel of conductive material and adapted to contain the liquid or solution, a tube of non-conducting material and having its lower end inserted in the said liquid or solution, a cap of conducting material and held on the upper end of the said tube, means connected with the said cap for draw-

ing the liquid or solution up in the tube, an electric circuit connected at one end with the said vessel and at its other end with the said cap, a voltmeter in the said circuit, a double switch in the said circuit, and a main or supply circuit connected with the said switch.

TIMOTHY HENRY REARDON.
